UNITED STATES PATENT OFFICE.

AUGUST W. NELSON, OF SPOKANE, WASHINGTON.

ELECTRICAL RAILWAY-SIGNAL.

No. 813,662.

Specification of Letters Patent.

Patented Feb. 27, 1906.

Application filed May 11, 1905. Serial No. 259,859.

To all whom it may concern:

Be it known that I, AUGUST W. NELSON, a citizen of the United States, residing at Spokane, in the county of Spokane and State of Washington, have invented new and useful Improvements in Electrical Railway-Signals, of which the following is a specification.

My invention relates to improvements in electric railway-signals; and the object is to provide an electrically-operated railway-signal which may be applied to uses on a straight track, but is especially designed for use to give required signals on curves of a track where the entrance and egress from the curve cannot be seen at the same time under ordinary circumstances. Therefore I provide lights and signals at each end of the section which are displayed simultaneously at each end of the curve and by trains moving in either direction.

It may be premised that the tracks may be multiplied and the connections and appliances suitably disposed in operative arrangement.

I accomplish the objects of my improvements by the means, mechanism, appliances, and aggroupments of parts illustrated in the annexed drawings, all of which will be fully described hereinafter, and then the asserted novelty will be particularly pointed out and distinctly claimed.

In the drawings, wherein similar elements and parts are designated by like reference notations in the several illustrations, Figure 1 is a diagrammatic view showing a curved section of a track and my improvements as applied thereto. Fig. 2 is a view in elevation of a supporting-post having my improvements mounted thereon. Fig. 3 is a view in elevation of the signal-casing with the front plate removed and showing the arrangement of the semaphore, the operating-magnet, and the bell, also indicating the circuits controlling these elements. Fig. 4 is a vertical transverse sectional view of a rail and illustration of the mechanism for effecting the contact which closes the circuits.

Referring to the drawings, 1 designates a railway-track, the rails 2 of which are laid to produce a pronounced curve therein, as indicated. Preferably within the curve is arranged a metallic circuit composed of wires 3 4, carried on suitable supports and cross-bars, as at 5. A battery 6 is positioned 55 at a proper location and the opposite limbs 7

8 thereof connected to the wires of the circuit to complete the same, substantially as indicated in the drawings.

On each of the posts at the terminals of the guarded section or curve is mounted a signal 60 housing or casing 9, having glass bull's-eyes or disks 10 disposed therein, through which the rays of the lamp are thrown in the usual manner. It may be stated that the glasses may be multiplied, so that each track may 65 be guarded by designated lights illuminated through circuit connections, as heretofore alluded to. In the housing in proper relation to the glass is properly mounted and secured an electric lamp or light 11, having circuit 70 connections with the main-line wires 3 4 by wires 13 14, as indicated in Fig. 3 of the drawings. Also an alarm 15 is provided. This may be of any approved type and has connections to the main-wire circuit by wires 16 75 17.

18 designates an electromagnet in circuit with the main wires 3 4 by wires 19 20. The semaphore 21 is pivotally supported in the housing and has the short arm 22 extending 80 to the rear of its pivotal support and adapted to be drawn down into contact with the core of the magnet when that member is electrically energized, and thus display the semaphore. 85

It will be perceived that when the current is in force on the main circuit the magnet will be energized and the semaphore thrown up. At the same time the light will be made to glow and the bell or alarm operated. To effect this simultaneous action, I have devised a device actuated by the passing wheels of the cars. This device comprises a bottom or foundation piece 23, shaped to set over and on the T-flange of the rail and formed with a 95 vertical hollow sleeve 24, wherein is slidably disposed the stem 25 of a bearing-yoke 26, between the arms of which is journaled a roller 27, arranged in the path of the wheel-flange, as indicated in Fig. 4 of the drawings. The yoke carries a contact-piece 28, having connection to one of the main-line wires, and is adapted to be depressed into contact with a companion contact-piece 29, secured to the sleeve 24, and has connection 100 to one of the main-line wires by wire 30 and leading to a limb of the battery. It will be perceived that the main circuit stands normally open and the semaphore at "safety," 105 but that when the roller 27 is depressed the 110

circuits are all completed and actuate all the warning elements simultaneously. These contact devices are positioned at determined points apart throughout the block or curve 5 to be guarded, the distance between them being such that the succeeding contact will be made before the wheel leaves that at the rear of it, and thus the continuity of the circuit be maintained. To return the roller to normal 10 position and thus separate the contacts, an expanding spring 31 is lodged in the bore of the sleeve 24.

What I claim is—

1. The combination with an electrical signal and a circuit connected therewith standing normally open, of contacts comprising a base-piece, a yoke slidably disposed in the base-piece, a roller journaled in the yoke in the path of the wheels of a passing car, contacts fixed to the base-pieces and to the

yoke, and adapted to contact when the roller and the yoke are depressed.

2. The combination with an electrically-operated signal, and a circuit connected therewith and standing normally open, of contacts 25 comprising a base-piece formed with a vertical sleeve and adapted to be secured to the bottom flange of a rail, a yoke slidably disposed in the said sleeve, a spring to lift and hold the yoke in upper position, a contact-piece secured to the yoke, and connected to the circuit, a contact-piece secured to the said sleeve, and a roller journaled in the yoke in the path of a passing car.

In testimony whereof I affix my signature 35 in presence of two subscribing witnesses.

AUGUST W. NELSON.
